US00D982979S

(12) United States Design Patent (10) Patent No.: US D982,979 S
(45) Date of Patent: * Apr. 11, 2023

(54) BEVERAGEWARE

- (71) Applicant: ANCHOR HOCKING, LLC,
Columbus, OH (US)
- (72) Inventors: Paul Gebhardt, Columbus, OH (US);
Karen MacNeil, Columbus, OH (US);
Diane Shane-Schuldt, Sherrill, NY
(US)
- (73) Assignee: ANCHOR HOCKING, LLC,
Columbus, OH (US)
- () Term: 15 Years
- (21) Appl. No.: 29/813,923
- (22) Filed: Nov. 2, 2021

Related U.S. Application Data

- (63) Continuation of application No. 29/686,099, filed on
Apr. 2, 2019, now abandoned.
- (51) LOC (14) Cl. 07-01
- (52) U.S. Cl.
USPC D7/524; D7/537
- (58) Field of Classification Search
USPC D7/509, 522-524, 537
CPC A47G 19/22; A47G 23/0208; A47G
2400/045; A47G 19/2205; A47G 23/0216

(57) CLAIM

The ornamental design for beverageware, as shown and described.

DESCRIPTION

The FIGURE is a front perspective view of beverageware showing our new design, where the rear perspective view,
the left side perspective view, and right side perspective view are a mirror image thereof.

1 Claim, 1 Drawing Sheet
